UNITED STATES PATENT OFFICE

ROBERT GEORGE, OF PARIS, FRANCE, ASSIGNOR TO CHENEY BROTHERS, OF NEW YORK,
N. Y., A CORPORATION OF CONNECTICUT

DESIGN FOR A TEXTILE FABRIC

Application filed September 16, 1932. Serial No. 44,862. Term of patent 3½ years.

To all whom it may concern:

Be it known that I, ROBERT GEORGE, a citizen of Switzerland, residing at 14 Rue du 4 Septembre, Paris, in the Republic of France, have invented a new, original, and ornamental Design for Textile Fabrics, of which the following is a specification, reference being had to the accompanying drawing, forming part thereof.

The figure is a plan view of a textile fabric showing my new design. The area within the

dot and dash lines shows one complete unit of the design. The repeats are arranged in vertical rows, and adjacent vertical rows are one half a complete unit offset so that the angle of the complete unit indicated by letter A corresponds with the angle B of one of the repeats in an adjacent vertical row.

I claim:

The ornamental design for a textile fabric, substantially as shown and described.

ROBERT GEORGE.
